(57) **CLAIM**

The ornamental design for a vacuum cleaner wheel, as shown and described.

DESCRIPTION

FIG. 1 is a front perspective view of a vacuum cleaner wheel, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a cross sectional view taken along the lines 9-9 of FIG. 1.

The broken lines illustrating portions of a vacuum cleaner wheel form no part of the claimed design.
